CLAIM

The ornamental design for a speaker enclosure, as shown and described.

DESCRIPTION

FIG. 1 is a top perspective view of the speaker enclosure, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an environmental view depicting the combination of the speaker enclosure and a speaker body.

The broken lines in FIG. 8 are for the purpose of illustrating surrounding environment that form no part of the claimed design.
